FLUID DISCHARGE DEVICE

Shung Moon, River Rouge, Mich.

Application September 14, 1940, Serial No. 356,843

1 Claim. (Cl. 251—24)

This invention relates to the class of sprinkling, spraying and diffusing and pertains particularly to improvements in sprayer devices designed primarily for use in moistening clothes preparatory to ironing.

The primary object of the invention is to provide a novel compact sprayer head or nozzle which is designed to be attached to a hose to receive water directly from a domestic water supply system, the nozzle being so designed that the application of pressure upon an element thereof releases a valve diaphragm which permits the water to shift the diaphragm from its seat and flow through for discharge from the nozzle tip.

Another object of the invention is to provide a spray device wherein a head, provided with a diffusing nozzle, carries a shiftable diaphragm which is normally maintained upon a seat by a hand actuated handle, said diaphragm when released by the actuation of the handle being shifted from its seat to permit water under pressure to pass through the nozzle for discharge from the tip in the form of a fine spray.

A further object of the invention is to provide a spraying device of the character stated wherein a novel means is provided to facilitate the ready adjustment of the degree of fineness of the water spray discharged from the nozzle.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claim.

In the drawing:

Fig. 1 is a top plan view of the sprayer embodying the present invention.

Fig. 2 is a sectional view on the line 2—2 of Fig. 1.

Fig. 3 is a view in elevation of the rear end of the sprayer.

Fig. 4 is a view partly in section and partly in side elevation of a modified form of the sprayer.

Referring now more particularly to the drawing, the numeral 1 generally designates the body or head of the spray device embodying the present invention. This body may be cast or otherwise suitably formed of any suitable material and it is provided with a tapered forward end portion 2 and at its rear with the integral coupling nipple

3 provided to facilitate the attachment to the head of a hose or other suitable conduit 4 by means of which water may be conveyed from a water supply system to the nozzle.

5 In the rear of the nozzle body there is formed an annular recess 5, which is concentric with and opens into the chamber 6 which is formed longitudinally through the body and which provides the receiver for water to be discharged from the forward end through the nozzle aperture 7. The forward end of the elongated water chamber 6 tapers off, as indicated at 8, to the nozzle 7 and this taper is made use of for securing in position in the forward end of the 10 chamber 6, the core 9 which functions to impart a whirling motion to the water as it issues from the nozzle aperture 7. This body 9 is formed of a relatively soft metal such as aluminum or brass and the side surface is provided with the plurality 15 of spiral grooves or channels 10 along which the water flows in passing between the body 9 and the tapered portion 8 of the water chamber wall. The degree of fineness of the spray issuing from the nozzle 7 may be controlled by regulating the 20 extent to which the spiral core body is forced into the tapered end 8 of the water chamber, it being readily obvious that as the core body is forced into the taper, it will be mashed or compressed and will reduce the size of the spiral 25 grooves or channels. Thus the farther the core body is forced into the taper, the finer will be the 30 water spray issuing from the nozzle 7.

The nozzle passage 7 is protected from damage through the tip of the body being struck against 35 objects, by being set back in the tip, and the end of the tip is counterbored or chamfered, as indicated at 11, whereby to permit the spray as it issues from the nozzle to spread in the desired manner.

40 The forward part of the annular recess 5 into which the water passage or chamber 6 opens is formed to provide the annular water channel 12, which encircles the rear end of the passage 6. By the formation of this channel there is thus 45 provided an annular seat 13 for a valve disk 14 formed of rubber or other suitable material. This valve disk is maintained in position adjacent to the seat 13 so that the portion adjacent the seat may have limited movement relative to the seat 50 permitting it to shift off of the same, under the effect of water pressure applied thereto, the retention of the diaphragm being effected by the ring 15 which is secured to the wall of the recess either by a press fit or by screw threads, as shown.

Extending through and from the nipple 3 is a water passageway 16 which at its forward end is reverted, as indicated at 17, to open into the bottom of the annular water channel 12. Since the overall diameter of the water channel 12 is less than the diameter of the recess 5 and of the valve disk 14, it will be readily seen that the valve disk or diaphragm when pressed against the seat 13, will effectively close the channel.

Extending longitudinally in the top of the body 1 is a slot 18 across the rear end of which a pivot pin 19 is secured. The rear end of this slot is in communication with the annular recess 5 and there is disposed within the slot the handle 20 which is pivotally supported upon the pin 19 and which has the laterally turned rear end portion 21 which terminates in the reversely extending finger tip 22, which is disposed substantially upon the axial center of the water chamber 6. Thus the finger 22 will be disposed at the rear of the center of the diaphragm valve and when the forward end of the handle is raised to oscillate the handle on the pin 19, the finger 22 will move toward the diaphragm.

Interposed between the finger 22 and the diaphragm is a disk 23 of metal or other suitable material which functions as a bearing plate against which the finger engages when the handle is oscillated in the proper direction to move the finger forwardly for the purpose of pressing the valve diaphragm against the seat 13.

Constant application of pressure against the disk 23 and diaphragm 14 by the finger 22 is effected by placing a suitable expansion spring 24 beneath the forward end of the handle 20, locating the ends of the spring in the opposed recesses 25 and 26 formed respectively in the handle and in the body. By this means, the spring is retained in position and can function freely to oscillate the handle in the desired direction to maintain the valve diaphragm upon its seat.

From the foregoing, it will be readily apparent that with the spray device of the present invention, a constant supply of water under pressure can be kept ready at hand for discharge in a fine spray over clothes or other objects and when the spray body is taken in the hand and pressure is applied to the handle 20, the diaphragm valve will be released so that it is free to shift from its seat. This permits the water to force its way from the channel 12 past the valve and into the chamber 6 to flow forwardly and be discharged through the nozzle 7. As previously stated, as the water passes the spirally grooved plug 9, it will be given a rotating motion and will

issue from the nozzle in a whirling fine spray, the degree of fineness being governed by the extent to which the plug is forced into the tapered forward end of the chamber.

While there has been shown a nipple 3 which is cast or otherwise formed integrally with the body 1, it is to be understood that there is no desire to limit the construction of the spray device to this specific design and it will be readily apparent that other means may be employed for attaching a hose or other fluid carrying pipe to the head as, for example, as shown in Fig. 4, the body may have a short tube 27 inserted thereinto in alignment with the water receiving passage which is here indicated by the numeral 16', which will function in the place of the nipple to be coupled with a hose or other fluid supply pipe.

What is claimed is:

A fluid discharge device, comprising a body having a forward end portion and having a water chamber extending longitudinally therethrough and communicating at one end in one portion of the body with an outlet, the body being provided at the opposite end of the water chamber with a recess into which the water chamber opens, the bottom of the recess being provided with an annular channel encircling the chamber, the material of the body between the channel and the water chamber forming an annular valve seat, means for conducting fluid into the annular channel, a diaphragm valve disposed in the recess over the channel and said seat, means engaging the diaphragm at its periphery for establishing a water-tight connection between such periphery and the wall of the recess at the outer side of the annular channel, a slot formed longitudinally in the side of the body and extending across but spaced from the outer side of the channel, the slot leading, at the end remote from the outlet, into the recess upon the side of the diaphragm away from said outlet, a handle disposed within said slot and pivotally supported for oscillation on an axis extending transversely of the body, the handle at one end having an inturned portion lying in the said portion of the slot leading into the recess, a finger extending from the inturned portion of the handle toward the center of the diaphragm, a pressure receiving element interposed between the finger and the diaphragm, and resilient means lying in the slot beneath the handle and constantly urging oscillation of the handle in a direction to move the said finger toward the diaphragm to effect compression of the same against the seat.

SHUNG MOON.
